Patented Nov. 16, 1976

242,357

CASING FOR AN ELECTRONIC CALCULATOR

Charles W. Kellstedt, Jr., Sudbury, Mass., assignor to The
Gillette Company, Boston, Mass.

Filed Mar. 21, 1975, Ser. No. 560,970

Term of patent 14 years

Int. Cl. D18—01

U.S. Cl. D26—5 C

Fig. 1

Fig. 2

*Fig. 3**Fig. 4**Fig. 5**Fig. 6*FIG. 1 is a perspective view of a casing for an electronic calculator showing my new design;

FIG. 2 is a rear elevational view thereof;

FIG. 3 is a top plan view thereof;

FIG. 4 is a bottom plan view thereof;

FIG. 5 is a right end elevational view thereof; and

FIG. 6 is a left end elevational view thereof.

The side of the casing for an electronic calculator, not shown, is a mirror image of the side shown in FIG. 2.

I claim:

The ornamental design for a casing for an electronic calculator, as shown and described.
